UNITED STATES PATENT OFFICE.

ADOLPH G. KAUFMAN, OF NEW YORK, N. Y.

HYDROCARBON-LAMP.

1,142,814.

Specification of Letters Patent. Patented June 15, 1915.

Application filed June 1, 1914. Serial No. 842,162.

To all whom it may concern:

Be it known that I, ADOLPH G. KAUFMAN, a citizen of the United States, residing at New York, in the county and State of New York, have invented a new and useful Hydrocarbon-Lamp, of which the following is a specification.

This invention relates to hydrocarbon lamps, and especially to that class in which the gasolene, kerosene, alcohol, or the like, is gasified and burned in connection with an incandescent mantle; and the objects of my invention are: 1. To provide a lamp of this kind which can be easily kept clean so that it will operate with the highest efficiency; 2. to provide a lamp of this kind with means to prevent the breakage of the mantle, or mantles in cleaning; 3. to provide an efficient construction in which natural breakage will not cause serious annoyance; 4. to provide a lamp with ready and simple means for removing the parts necessary to be cleaned, and the utilization of these means relative to the convenience of putting the lamp in operation; 5. to provide a lamp of this kind with parts so constructed that a cleaning needle can be easily inserted, and, at the same time, the noise in operation will be largely eliminated; and 6. to provide a hydrocarbon lamp that is cheap to manufacture, efficient in use, and attractive in appearance.

In the construction of hydrocarbon lamps using a mantle, or mantles, it is customary to provide a vaporizing tube in which the hydrocarbon is gasified, and from which it is discharged through a very small orifice. As this tube is usually very hot considerable carbonization takes place at this orifice in the discharge nozzle thereby requiring the frequent insertion of a "needle" to clear the orifice.

As usually constructed lamps are provided with two burners and mantles; and it is a very difficult matter to "needle" the orifice in the nozzle without breaking one, or both of the mantles even if the needling is done through the air intake. If the vaporizing tube is removed from the lamp to needle the same, the breakage of the mantle, or mantles is even more certain.

I have found it desirable to use wire screens in the air intakes to prevent dirt

being drawn into the lamp; and these screens prevent the insertion of a needle in 55 the nozzle orifice through the air-intake, necessitating the removal of the vaporizing tube each time the orifice has to be needled.

As the vaporizer must be removed each time, I have provided simple and efficient 60 means to remove and insert the same without breaking either mantle; and have also provided simple and efficient means to prevent the annoyance of breakage of a part of the vaporizer in removing, or inserting, which 65 will be hereinafter pointed out. I have also provided the vaporizer with simple means to tighten, and unscrew the same without requiring the use of a tool; and have also provided the vaporizer with a nozzle of special 70 construction which will not only lend itself to the easy removal, and insertion of the vaporizer; but which also renders the needling of the same very easy, and at the same time provides means to reduce the 75 noise of operating the lamp.

The invention is illustrated in the accompanying drawing, in which—

Figure 1, is a side elevation, partly in section, of a lamp constructed in accordance 80 with my invention; Fig. 2, is a front view, partly in section, of the upper portion thereof; and Fig. 3, is a vertical section of the nozzle, mounted on the vaporizing tube.

In the drawing, like numerals of reference 85 refer to the same parts in each of the views.

In the drawing I have shown only the structural part of the lamp without reference to a reservoir, or means for holding the hydrocarbon, or feeding the same to the 90 vaporizing tube. As such reservoirs, and feeding means are variously constructed, and also well known, any one skilled in the art will understand these parts without illustration.

In practice I provide an upper structure consisting of an air-intake 4, mixing chamber 5, burner tubes 6, 6, carrying mantles 7, 7; and a lower structure consisting of the needle valve casting 8, with controlling 100 wheel 9, vaporizing tube 10, with nozzle 11 and connection 12, with a reservoir; and I connect the upper and lower structures with a single standard 13, which may be mounted on an arm 14, of the needle valve casting, 105 said standard having a feathered connection

15, to prevent turning, and being secured rigidly in place by a nut 16. The upper structure will thus be held rigidly in place whereby the air-intake will have one entrance directly over the standard 13, and the other entrance on the opposite side of the lamp while the burner tubes and mantles will be held in fixed positions on the opposite sides of said air-intake, and of the 5 vaporizer which enters the air mixer substantially central of the air-intake.

The air-intake has a perforation 17, through which the nozzle 11, of the vaporizer may enter; and the lower end of the vaporizer 15 is provided with the usual reduced screw-threaded part 18, whereby the height of the nozzle within the air mixer may be regulated, as will be readily understood.

Where the reduced part 18, is screwed into 20 a solid casting, or forging, owing to the frailness of the same it is frequently broken, and causes a great deal of trouble in the removal of the portion of the part 18, left in the socket. To avoid this trouble I have provided a bushing 19, which I mount in the part 8, or in whichever part the vaporizer tube is usually mounted; and I screw the reduced part 18, into this bushing. Thus, if the part 18, should be broken in the 25 socket, I can easily remove the bushing 19, and extract therefrom the portion of the part 18, contained therein, or I can substitute a new bushing. I am thus able to remove the vaporizer, and reinsert the same, 30 or renew the same with very little trouble.

In order that the vaporizer may be removed, and reinserted without breaking the mantles, I have provided the end of the air-intake piece opposite the standard 13, with 40 a channel 20; and the air-intake piece is also preferably provided with a ledge, or shoulder 21, abutting on the opening 17. Thus, in inserting the new vaporizer, the end is inserted in the channel 20, as indicated in dotted lines in Fig. 1; and then by sliding the 45 vaporizer inward the nozzle will strike against the shoulder 21, which will act as a stop, and also as a guide to direct the nozzle upward through the orifice 17. The lower 50 end of the vaporizer can be then carried inward with little danger of breaking either mantle since the upper end is held rather rigidly; and the part 18, can be screwed into its socket. Thus by having the guiding 55 channel 20, and the shoulder 21, the vaporizer may be easily removed, and replaced without causing damage to either mantle. It will be understood, however, that this 60 feat is the more readily accomplished owing to the fact that but a single standard 13, is used.

In order that the vaporizer may be more readily entered in the way described, I prefer to provide the nozzle 11, with flat sides 65 22; and these sides also furnish ready means

for engagement with a wrench to unscrew the nozzle from the vaporizing tube.

In order that the vaporizer may be the more easily removed and reinstated, I prefer to braze, or otherwise secure on the vaporizer tube a knurled cup 23, which may be used as a starting cup by placing therein asbestos 24, into which alcohol may be poured for burning when starting the lamp. This cup 23, therefore performs the double 75 function of providing a ready means for adjusting, or removing the vaporizer, and of providing a starting cup when putting the lamp into operation.

In order that the nozzle may be readily 80 needled when removed from the lamp, I provide a countersunk portion 25, above the orifice 26; and this countersunk portion will act as a guide for the needle so that the needle can be inserted in the orifice 26, with 85 little difficulty. This not only adds to the convenience of needling the nozzle, but the countersunk portion allows for the expanding of the gas after passing the orifice but before leaving the nozzle entirely; and this 90 seems to materially lessen the noise of operating the lamp. Inserting the nozzle in the end of the vaporizing tube 10, instead of mounting the same on the end of the tube as a cap, as is generally done, gives more 95 directness to the flow of gas and reduces the noise of operation.

The entire construction works together to 100 form a lamp of great efficiency, desirability, and compactness.

I claim:

1. A hydrocarbon lamp having a plurality of mantles, and a vaporizer mounted intermediately of said mantles, said lamp having a guide extending in a lateral direction 105 from without the zone of said mantles to the normal position of said vaporizer whereby the movement of said vaporizer is guided from contact with any of said mantles during the renewal of the vaporizer.

2. The combination with a hydrocarbon lamp of an air-intake piece having a standard connected with one end thereof, said air-intake being perforated to receive the nozzle of the vaporizer, and having a channel formed in the under side thereof from 115 said orifice to the free end, for the purpose set forth.

3. The combination with a hydrocarbon lamp of an air-intake piece having a standard connected with one end thereof, said air-intake piece being perforated substantially centrally thereof to receive the nozzle of the vaporizer, and having a channel formed in the under side thereof from 120 said perforation to the free end, and having a shoulder on the side of said perforation opposite said channel, for the purpose set forth.

4. A hydrocarbon lamp having a plural- 130

ity of mantles, and a vaporizer mounted intermediately of said mantles, said lamp having a guide adapted to direct the movement of said vaporizer during the renewal of the 5 same, and said vaporizer having a knurled cup fixed thereon without the zone of said mantles whereby the vaporizer may be se-

cured in position with the hand of the operator alone.

Dated 29th day of May, 1914.

ADOLPH G. KAUFMAN.
